Primary Examiner — Thomas Johannes(74) *Attorney, Agent, or Firm* — Dennis J. Williamson; Moore & Van Allen, PLLC(57) **CLAIM**

We claim the ornamental design for a package and a window covering, as shown and described.

DESCRIPTION

FIG. 1 is a perspective view showing our new design for a package and a window covering;

FIG. 2 is a back elevation view thereof;

FIG. 3 is a front elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken line portion of the figure drawings is included to show unclaimed subject matter only and forms no part of the claimed design.
